William Jones. Haverstraw Rockland Co. N.Y.

Letters Patent.

The Schedule referred to in these Letters Patent word-making part of the same containing a description in the words of this said William Jones himself of his improvement in the machine for pressing out puddles, Bally & other iron instead of hammering the same out.

To all to whom these presents shall come.

Be it known that William Jones of Haverstraw in the County of Rockland under State of New York have invented a new & useful machine — for pressing out puddles, Bally & other iron instead of hammering the same out and that the following is a full and exact description of said machine as invented by me.

First — The machine consists of a beam of cast iron called the squeezer moving on a pivot by means of a lever & crank & a cast iron bed on which the iron and Bally to be pressed out are placed. — The squeezer is of a triangular form and may be single or double resembling two triangles joined at their bases —

2nd — The centre of the squeezer carries a pair of weights on which the squeezer turns — This prevents one side from supporting pressing upon each side of the squeezer. The top of the supports being of an oval form extending along the sides of the squeezer to prevent cracking — one of the supports is cast solid with the bedplate, the other is removable, a plow being fastened between two strings attached to the bedplate by means of wedges — The bed consists of a cast iron plate of about four inches thickness — The squeezer is moved in various ways. The most simple is by means of a lever to the end of which is attached a connecting rod passing diagonally to a crank & placed at a convenient distance. The entire machine

Drawn

is supported on a strong frame made of wood or iron about 12x18 feet in height. When at rest the space at the mouth or end of the machine between the squeezer and the bed is about 15 inches $\frac{3}{4}$ at the throat about four inches.

The iron or balls to be pressed out are placed on the bed at the mouth of the press & gradually pushed forward towards the anterior throat at each revolution of the crank.

The pressure arising from four to six inches at each revolution may be increased or diminished at pleasure.
